(57) **CLAIM**

The ornamental design for an all-steel electric and gasoline agricultural all-terrain vehicle, as shown and described.

DESCRIPTION

FIG. 1 is a front and left side perspective view of an all-steel electric and gasoline agricultural all-terrain vehicle embodying our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is an interior perspective view thereof taken from the left side; and,

FIG. 9 is an interior perspective view thereof showing the dashboard and steering wheel.

1 Claim, 9 Drawing Sheets
